EXHAUST HOOD

Isaac M. Baker, Jr., 1323 Windsor Point Road,
Norfolk, Va.

Filed Aug. 22, 1961, Ser. No. 133,102
3 Claims. (Cl. 261—16)

This invention relates to exhaust hoods for use in removing heat and dirt or grease-laden air from a designated area, usually a cooking area, and particularly to exhaust hoods which utilize liquid sprays for cleaning the air so removed.

It is common practice to place a hood over a cooking area and, by means of a fan, draw air from the area and exhaust it to atmosphere, to prevent accumulation of heat in the area, and to remove grease which may rise from the cooking utensils. With prior device, it has been difficult to get access to all interior parts of the hood for cleaning. Consequently, grease has accumulated in the hood, creating a fire hazard and frequently causing unpleasant odors.

The general object of the present invention is to provide an improved exhaust hood which will efficiently remove heated air and grease-laden air from the area it is to serve.

A more specific object of the invention is to provide an exhaust hood which is constructed so that its interior structure may be readily removed for ease in cleaning and to provide ready access to all of the interior surfaces of the hood proper.

Another object is the provision of such a hood where a washing fluid is used to scrub the air drawn into the hood to separate the grease for collection, so that no grease escapes into the stack for entrapment.

A further object is to provide a hood of this nature which is partially self-cleaning, to the extent that the air or gas washing liquid is caused to flow over the interior surfaces of the hood to wash them.

Yet another object of the invention is to provide an exhaust hood wherein a supply of washing fluid will be available for cleaning the hood, without the necessity for obtaining a supply from another source.

Other objects of the invention will become apparent from the following description of one practical embodiment thereof, when taken in conjunction with the drawings which accompany, and form part of, this specification.

In the drawings:

FIGURE 1 is a front elevational view of an exhaust hood incorporating the principles of the present invention;

FIGURE 2 is a top plan view of the exhaust hood;

FIGURE 3 is a somewhat diagrammatic view, showing the hood in side elevation and connected to a typical liquid supply system;

FIGURE 4 is a vertical, transverse section through the hood, taken on the line 4—4 of FIGURE 1 and shown on an enlarged scale; and

FIGURE 5 is a detail section showing the removable liquid collection pans, and is taken on the line 5—5 of FIGURE 4.

In general, the invention contemplates an exhaust hood which has means for spraying liquid over a path through which air is drawn, in order to remove the grease, or other dirt, from the air. The sprayed liquid and condensate, together with removed grease, are caught in removable collection pans and in a perimetral drain trough for delivery to a common outlet sump. The hood may be supplied with fresh air for mixture with dirty air to be cleaned, and as a means for entrainment of the

2

air to be cleaned, and the spray liquid may carry a detergent, if desired.

Referring to the drawings in detail, the hood will be constructed upon a frame 1, which may include front and back rectangular members 2 and 3, interconnected by top bridge members 4. Sheet metal back plate 5, front plate 6, top plate 7, and end plates 8 are fixed to the frame members to provide an outer housing having a bottom opening and a bottom edge 8a.

The top plate 7 is divided by spaced angle irons 9, which extend the length of the hood, to provide a longitudinal opening 10 to receive the lower open end of an exhaust stack 11. The stack has deflector plates 12 along its lower longitudinal edges, and the two deflectors converge downwardly. A plurality of inclined struts 13 extend from the rear lower edge of the stack to the rear lower edge of the outer housing of the hood. A plate 14 is carried by the struts to form the inner rear wall of the hood. Plate 14 terminates short of the bottom wall of the hood, providing an elongated entrance port 15 for auxiliary air. The rearward part of top plate 7, the back plate 5 and the plate 14 define an air manifold 16, and the port 15 forms an outlet from the manifold extending the length of the hood. A suitable air inlet casing 17 supplies air to the manifold. The front inner wall of the hood is formed by a concavely curved plate 18, which has its rear edge at the bottom edge of the front deflector 12.

Along the bottom of the front inner wall, and along the side walls, there is an open perimetral trough 19 to collect spray, condensate and grease which may run down the front and side walls. The trough opens at both ends to the ends of a main trough 20 spaced adjacent the bottom edge of the back plate 5 and which extends along the rear of the hood just to the front, and below, the port 15. The main trough slopes toward one end of the hood to provide for drainage, and the perimetral trough along the front wall slopes in the same direction. The legs of trough 19, along the side walls, slope toward the main trough, so that complete drainage of the perimetral trough into the main trough will be effected. A suitable drain pipe 21 will be connected to the main trough at its low point.

There are a plurality of collection pans 22 and 23 within the hood, arranged in side-by-side relation the full length of the hood. The pans lie beneath the open bottom of stack 11 to catch liquid from spray nozzles 24 attached to a liquid supply pipe line 25 within the bottom of the stack and extending the horizontal length of the stack. The pans decline rearwardly to a position overlying the main trough 20, so that fluid falling on the pans will drain into the main trough. The pans are supported at their base ends upon a rod 26, which is carried by hangers 27, mounted upon the front inner wall 18. The rear ends of the pans rest upon an angle iron 28 which extends the length of trough 20. Brackets 29, fixed to the back inner wall 14 and the front wall of trough 20, support angle iron 28.

Pans 22 and 23 are identical insofar as both types have flat bottoms 30, vertical side walls 31, an inclined front wall 32 and declining rear apron 33. The pans differ in that the side walls 31 of pans 23 are turned over at their tops to provide downturned flanges 34 spaced from the side walls, forming locking grooves to receive the tops of the straight side walls of adjacent pans 22. The pans are arranged in side-by-side position with pans 22 and 23 alternating. Flanges 34 of pans 23 will overhang the side walls of adjacent pans 22, so that the entire group will be intercoupled and there can be no transverse separation of the pans.

Each pan carries a channel-shaped section 35 along

the front edge of the bottom. The sections 35 are beneath the pan bottoms and open downwardly to straddle rod 26 and hold the pans in operative position. As the channels fix the pan positions, it is only necessary that the back ends of the pans rest upon the angle support 28.

When the hood is installed, a fan (not shown) will be located in stack 11, or at its outlet, to draw air from the area beneath the hood, through the hood, and also draw an air supply through inlet casing 17, air manifold 16 and air port 15. Another fan (not shown) may be used in inlet 17 to force air through port 15.

It is contemplated that the hood will be incorporated in a liquid supply system which will provide constant recirculation of the liquid. Such a system is shown diagrammatically in FIGURE 3. The liquid supply pipe 25 may be connected to a pump 36, located in the sump of a supply tank 37. A detergent metering and density control device 38 will have its feed pipe 39 coupled to the supply tank 37, so that detergent will be supplied in proper proportion to, and pumped with, the liquid. Tank 37 may have a fresh liquid supply line 40, controlled by a float valve 41 to maintain the liquid at a constant level. The level will be high enough to provide for a constant bleed-off through outlet pipe 42. The drain line 21 from the exhaust hood main trough will empty into tank 37. Any grease returned to tank 37 by line 21 will float on the surface of the liquid in the tank and be carried off through the bleed-off through outlet pipe 42. The hood supply line 25 will be valved, as at 43, and a branch line 44 may be used, emptying into the perimetral trough 19. Line 44 will have a valve 45, so that liquid may be directed to the spray line 25 during general use of the hood, and into the trough 19, and from trough 19 to trough 20, to provide liquid supply when the hood is being cleaned.

In using the hood, it will be mounted horizontally on an area to be controlled. When the stack fan is on, air will be drawn into and through the hood and out stack 11, as previously described. Detergent liquid will be sprayed from pipe 25, so that the entire entrance to the stack will be covered and all air entering the stack must pass through the spray. The spray will be controlled by deflectors 12, so that it will fall into collection plates 22 and 23, to drain into main trough 20 and be carried back to tank 37 for recirculation. Air passing through the detergent spray will be scrubbed, so that grease and dirt will be removed and be carried off with the spray.

When it is desired to clean the hood, the pans 22 and 23 can be lifted from their supports and removed. This leaves the entire interior of the hood open, so that all parts of it may be reached for cleaning. Detergent liquid may be run through the trough 19, so that an ample supply will be directly available during cleaning. When the cleaning operation is completed, it is an easy matter to re-seat the pans upon their supports with the flanges 34 of pans 23 hooked over the upstanding sides 10 of pans 22.

While in the above one practical embodiment of the invention has been disclosed, it will be understood that the details of construction shown and described are merely by way of example, and the invention may take other 15 forms within the scope of the appended claims.

What is claimed is:

1. An exhaust hood comprising an enclosure having an open bottom and a bottom edge, a stack having an elongated opening communicating with the interior of 20 said enclosure through the top thereof, a liquid spray pipe in the stack adjacent the juncture of the enclosure and the stack, a trough supported on the enclosure spaced adjacent to a portion of the bottom edge, a plurality of 25 removably mounted collection pans disposed in side by side relation supported on the enclosure directly beneath the stack opening along the length thereof and above the level of said trough, said pans each having a length at least equal to the width of said stack opening to catch the liquid discharged from the spray pipe, said pans 30 declining toward the trough and having their lower edges overlying at least a portion of said trough to permit the pans to drain into the trough and a liquid drain line from the trough.

2. An exhaust hood as claimed in claim 1, wherein a 35 second trough is disposed adjacent and extends around the remaining portion of the bottom edge of the enclosure emptying into the first named trough.

3. An exhaust hood as claimed in claim 1, wherein an 40 auxiliary air manifold extends along the length of the enclosure having a port opening to the enclosure adjacent the trough.
